W. H. MEYER,

WASHING MACHINE.

APPLICATION FILED JAN. 14, 1920.

1,412,292.

Patented Apr. 11, 1922.

UNITED STATES PATENT OFFICE.

WILLIAM H. MEYER, OF ST. LOUIS, MISSOURI, ASSIGNOR, BY MESNE ASSIGNMENTS,
TO THE DAVIS SEWING MACHINE COMPANY, A CORPORATION OF DELAWARE.

WASHING MACHINE.

1,412,292.

Specification of Letters Patent. Patented Apr. 11, 1922.

Application filed January 14, 1920. Serial No. 351,290.

To all whom it may concern:

Be it known that I, WILLIAM H. MEYER, a citizen of the United States of America, a resident of the city of St. Louis, in the State 5 of Missouri, have invented certain new and useful Improvements in Washing Machines, of which the following is a full, clear, and exact description, reference being had to the accompanying drawings, forming a part 10 of this specification.

My invention relates to improvements in washing machines, and more particularly to power driven washing machines adapted to be actuated by a continuously running motor, which drives the clothes receptacle as 15 well as the wringer. One of the objects of the invention is to provide an improved means for transmitting movement from the motor to the clothes receptacle, said means 20 preferably including an oscillatory clutch device adapted to be connected to and disconnected from the clothes receptacle, thus allowing the clothes receptacle to remain at rest while the motor is driving the wringer.

Another object is to provide an improved 25 means for locking the clothes receptacle in a fixed position to prevent movement thereof when it is disconnected from the power mechanism. This locking means and the 30 clutch device for transmitting motion to the clothes receptacle are preferably under the control of a single operating member, which may be readily actuated to successively disconnect the clothes receptacle from the 35 power mechanism and to thereafter lock the clothes receptacle in a fixed position.

With the foregoing and other objects in view, the invention comprises the novel construction, combination and arrangement of 40 parts hereinafter more specifically described and illustrated in the accompanying drawings, wherein is shown the preferred embodiment of the invention. However, it is to be understood that the invention comprehends 45 changes, variations and modifications which come within the scope of the claims hereunto appended.

Fig. I is a side elevation of a washing machine, with a part of its housing broken 50 away to show the clutch device through which motion is transmitted from the power mechanism to the clothes receptacle.

Fig. II is an enlarged fragmentary side elevation, showing the clutch device and the

means for locking the clothes receptacle in 55 a fixed position.

Fig. III is a vertical section on line 60 III—III, Fig. II.

Fig. IV is a section on line IV—IV, 65 Fig. III.

Fig. V is a perspective view of a rotary sleeve adapted to cooperate with a cam for the purpose of actuating the clutch device.

A designates the frame of a washing machine, preferably enclosed in a housing 2. A 65 clothes receptacle, or tub 3, adapted to oscillate in the housing, is supported by suitable pivots, one of which is designated by the numeral 4 in Figs. I, II and III. Each side of the tub 3 is provided with a frame 3' rigidly 70 fixed thereto, as shown in Figs. I and III, and the pivot pin 4 may be riveted to said frame, as shown in Fig. III. A vertical sheet metal member 5, forming part of the stationary main frame, lies adjacent to the 75 pivot 4, and a tubular supporting member 6 is attached to this sheet metal member, as shown in Fig. III. 6' designates a sleeve located in the tubular member 6 to form a bearing for the pivot 4. An outer bearing 80 sleeve 6^a (Fig. III) is secured to the frame 3' on the tub to form a bearing for the oscillating clutch member, which will be herein- 85 after described.

7 designates a shiftable clutch member, 85 preferably in the form of a pin arranged radially to the pivot 4 and slidably mounted in a radial guide 8 (Figs. II and III), said guide being fixed to the frame 3' on the oscillatory tub of the washing machine. 90

An oscillating clutch member 10 is loosely mounted on the outer bearing sleeve 6^a (Fig. III), said bearing sleeve being fixed to the frame 3' on the tub. This oscillating clutch member 10 is preferably in the form of a 95 crank arranged to oscillate about the axis of the tub and provided with a recess or notch 11, adapted to receive the vertically movable clutch pin 7. The notch 11 is formed in the peripheral face of the crank arm, or clutch 100 member 10, and this peripheral face is concentric with the axis of the crank arm and tub. Since the crank arm 10 is loosely mounted on the bearing sleeve 6^a (Fig. III), said crank arm is free to move independently 105 of the tub, and it may be oscillated continuously without transmitting movement to the tub. However, when the clutch pin 7 is ex-

tended into the notch 11 in the crank arm, motion will be positively transmitted from said crank arm to the clutch pin 7, and consequently to the tub which carries the clutch 5 pin.

A motor M (Fig. I), which may be secured to the frame of the machine in any suitable manner, has a pulley 12 on its power shaft. A larger pulley 13, fixed to a shaft 14, is connected to the pulley 12 by a belt 15. A pinion 16 on the shaft 14 meshes with and drives a large gear wheel 17, the latter being fixed to a shaft 18 provided with a crank 19, to which a pitman 20 is pivoted. This pitman 15 is also pivotally connected to the oscillatory crank arm, or clutch member 10. By means of the mechanism just described, rotary motion will be transmitted from the motor to the shaft 18, and an oscillatory 20 movement will be imparted to the oscillatory clutch member 10. The motor and the oscillatory clutch member 10 may be driven continuously, and by means of mechanism to be hereinafter described, the operator can 25 very easily start and stop the tub without interrupting the motion of the clutch member 10. If the radially movable clutch pin 7 on the tub is disengaged from the oscillating clutch member 10, said clutch member 30 will be driven idly while the motor is in operation. If, however, the clutch pin 7 is moved downwardly and permitted to enter the notch 11 in the oscillating clutch member 10, the oscillatory movement will be 35 transmitted from the clutch member 10 to the tub.

The means for shifting the slidable clutch pin 7 includes a vertical shaft 21 mounted in bearings 5' (Figs. III and IV), which 40 may be formed by flanges extending from the vertical sheet metal member 5. This vertical shaft 21 also extends through flanges 22 on a cam plate B. As will be hereinafter described, the vertical shaft 21 may be moved 45 longitudinally to lock and unlock the tub, and it can be rotated to raise and lower the cam plate B for the purpose of moving the slidable clutch pin 7 into and out of engagement with the oscillatory clutch member 10. 50 An arcuate flange 22', extending from the cam plate B, lies in a notch in the clutch pin 7 (Fig. III), so as to interlock the cam plate with said clutch pin. The clutch pin is carried by the oscillatory tub, while the cam 55 plate B remains stationary when the tub is in operation. Therefore, the arcuate flange 22' on the cam plate is concentric with the axis of the tub, so the tub and clutch pin may be oscillated without transmitting movement 60 to the arcuate flange 22'.

The upper portion of the cam plate B is provided with an inclined cam slot 23, adapted to receive a projection 23' (Figs. III, IV and V) extending from a sleeve 24, 65 in which the vertical shaft 21 is slidably

mounted. A pin 21' (Fig. IV), extending from the vertical shaft 21, lies in a slot 24' (Figs. IV and V) formed in the sleeve 24. The shaft 21 can be moved vertically without transmitting movement to the sleeve 24, 70 but when the shaft 21 is rotated the pin 21' will cooperate with a wall of slot 24' to impart a corresponding movement to the sleeve 24, thereby moving the projection 23' in the inclined slot 23, with the result of imparting a vertical movement to the cam plate B, the latter being slidably mounted on shaft 21. When the cam plate is shifted vertically, its flange 22' cooperates with clutch pin 7 to move the latter into and out of engagement 80 with the oscillatory clutch member 10.

I will now describe the means for locking the tub in a fixed position to prevent movement thereof when it is disconnected from the driving mechanism. A locking member 85 27, in the form of a sleeve, is rigidly fixed to the vertical shaft 21, as shown most clearly in Figs. III and IV, and this locking member is provided with wings 28 and 29 whereby the tub may be locked in a fixed 90 position. The wing 28 is adapted to enter a notch 25' (Fig. III) formed in a flange 25 carried by the tub, said flange being extended from the frame 3' which is secured to the tub. The flange 25 is preferably inclined as shown 95 in Figs. II and IV to provide oppositely inclined faces leading to the notch 25'. The wing 29 (Figs. II and III) on the locking sleeve 27 is adapted to enter a notch 26 in a fixed part of the frame, so as to prevent rotation of the locking sleeve. A spring 30, surrounding the vertical shaft 21, lies between the locking sleeve 27 and a flange 5' on a fixed part of the machine, said spring tending to retain the locking sleeve in an 105 elevated position, shown in Fig. III, wherein it engages an intermediate flange 5' on a fixed part of the machine. It will therefore be understood that the spring 30 cooperates with the locking sleeve 27 to yieldingly hold 110 its wings 28 and 29 in notches 25' and 26.

To unlock the tub it is only necessary to force the vertical shaft downwardly, thereby lowering the locking sleeve 27 to remove its 115 wings 28 and 29 from the notches 25' and 26. After the vertical shaft 21 has been depressed to unlock the tub, said shaft may be turned, so as to turn the locking sleeve 27, thereby locating the locking wing 29 beneath a shoulder 31 (Fig. II) on a fixed part of the machine. The wing 29 will then cooperate with shoulder 31 to retain the locking device in its unlocked position.

It will be noted that a vertical movement 125 of shaft 21 does not displace the sleeve 24 on the upper end thereof, said shaft being slidably mounted in said sleeve 24 and provided with a pin 21' which, as previously pointed out, is free to move vertically in a 130

- slot 24' formed in the sleeve. A collar 32 (Fig. III), loosely surrounding the shaft 21, is interposed between the sleeve 24 and a fixed flange 5' to prevent downward movement of said sleeve. Upward movement of the sleeve 24 is prevented by a higher flange 5' which engages the top face of said sleeve. When the shaft 21 is rotated, a corresponding movement will be imparted to the sleeve 24 for the purpose of raising or lowering the cam plate B whereby the clutch pin 7 is actuated, as previously pointed out. 33 designates an operating handle fixed to the upper end of the vertical shaft 21.
- 15 It will now be readily understood that the operating handle 33 may be manipulated to successively unlock the tub and thereafter connect the slideable clutch pin 7 to the oscillating clutch member 10. When the operating handle 33 is forced downwardly, the shaft 21 and locking sleeve 27 will move downwardly from the position shown in Fig. III, so as to unlock the tub, and thereafter said operating handle and shaft may be turned to impart a corresponding movement to the sleeve 24 and its projection 23' which extends into the cam slot 23 in the cam plate B. The last mentioned movement of the operating handle and vertical shaft 25 will cause the projection 23' to cooperate with the cam plate B, so as to depress said cam plate. Since the arcuate flange 22' on the lower end of the cam plate is interlocked with clutch pin 7 (Fig. III), it will be understood that this downward movement of the cam plate will force the clutch pin into operative engagement with the oscillating clutch member. To disconnect the tub from the power mechanism, the operating handle 33 is turned with the result of elevating the cam plate B, thereby withdrawing clutch pin 7 from clutch member 10; and if the operating handle is then released, the spring 30 will force the shaft 21 in an upward direction so as to locate the locking wings 28 and 29 in their operative positions, shown in Fig. III, wherein they retain the tub in a fixed position. If the locking wing 28 does not register with notch 25' when the spring 30 moves the locking device upwardly, said spring will force the locking wing 28 into engagement with the bottom face of the inclined flange 25 in which the notch 25' is formed, and the tub can then be moved by hand to the position wherein it is to be locked. When the tub reaches this position the spring 30, acting an locking sleeve 27, will force the flange 28 (Fig. III) into the notch 25'.
- 60 I claim:
1. A washing machine comprising an oscillatory clothes receptacle provided with a guide on one of its side walls, a driven clutch pin slidably mounted in said guide, an oscillatory driving clutch member movable about
- the axis of said clothes receptacle, said driven clutch pin being movable toward and away from said axis so as to pass into and out of engagement with said oscillatory driving clutch member, and operating means 70 whereby said driven clutch pin is shifted in said guide to control the transmission of movement from said oscillatory driving clutch member to said clothes receptacle.
2. A washing machine comprising an oscillatory clothes receptacle provided with a radial guide on one of its side walls, a radial clutch pin slidably mounted in said guide, an oscillatory driving clutch member movable about the axis of said clothes receptacle, said driving clutch member comprising a crank arm notched to receive said radial clutch pin, said clutch pin being movable toward and away from said axis so as to pass into and out of the notch in said 80 crank arm, and operating means whereby said radial clutch pin is shifted in said radial guide to control the transmission of movement from said oscillatory driving clutch member to said clothes receptacle. 90
3. A washing machine comprising an oscillatory clothes receptacle, an oscillatory driving clutch member movable about the axis of said clothes receptacle, a driven clutch member mounted on said clothes receptacle and movable toward and away from said axis so as to pass into and out of engagement with said oscillatory driving clutch member, a support for said oscillatory clothes receptacle, a shifter supported 95 by said support, said shifter having an arcuate operating member interlocked with said driven clutch member, said arcuate operating member being concentric with said axis, and said shifter being movable to disengage 105 said driven clutch member on the clothes receptacle from said driving clutch member.
4. A washing machine comprising a support, an oscillatory tub pivoted to said support, a constantly oscillating clutch member having a recess formed therein, a vertically movable clutch member slidably mounted on said tub, a plate supporting said slidably mounted clutch member, and means cooperating with said plate for bringing 110 said slidably mounted clutch member into operative relationship with said oscillating clutch member.
5. A washing machine comprising a support, an oscillatory tub pivoted to said support, a continuously running motor, driving connections between said motor and said tub comprising a constantly oscillating clutch member, a vertically movable clutch member carried by said tub, a plate cooperating 115 with said vertically movable clutch member having a cam slot formed therein, the lower portion of said plate having an arcuate flange concentric with the axis of said tub, said flange being slidably inter- 120
- 65 125
- 65 130

locked with said vertically movable clutch member, and a means operating in the cam slot formed in the said plate for depressing the plate and bringing the vertically movable clutch member into operative relationship with said oscillating clutch member.

6. A washing machine comprising a support, a tub pivoted to said support, a constantly oscillating clutch member having a recess, a vertically movable clutch member carried by said tub, a plate cooperating with said vertically movable clutch member having a cam slot formed therein, a vertical rotatable shaft, a sleeve on said shaft having an extension which operates in the cam slot formed in said plate, and means for rotating said shaft to depress said plate whereby said vertically movable clutch member is brought into the recess in said oscillating clutch member.

7. A washing machine comprising an oscillatory tub, an oscillatory clutch member comprising a crank arm movable about the axis of said tub, said crank arm having a notch in its peripheral face, a clutch pin slidably mounted on said tub, said clutch pin being movable toward and away from the axis of said tub and crank arm, and operating means whereby said clutch pin is moved into engagement with said peripheral face and into the notch therein, said peripheral face being concentric with said axis.

8. A washing machine comprising an oscillatory clothes receptacle, an oscillatory driving clutch member movable about the axis of said clothes receptacle, a driven clutch member mounted on said clothes receptacle and movable toward and away from said axis so as to pass into and out of engagement with said oscillatory driving

clutch member, locking means adapted to retain said tub in a fixed position when said driven clutch member is disengaged from said oscillatory driving clutch member, an operating member common to said locking means and driven clutch member, and means whereby the movement is successively transmitted from said operating member to said locking means and then to said driven clutch member, the last mentioned means comprising a member movable in one direction to transmit movement to said locking means and movable in another direction to move said driven clutch member.

9. A washing machine comprising an oscillatory clothes receptacle, an oscillatory driving clutch member movable about the axis of said clothes receptacle, a driven clutch member mounted on said clothes receptacle and movable toward and away from said axis so as to pass into and out of engagement with said oscillatory driving clutch member, locking means adapted to retain said tub in a fixed position when said driven clutch member is disengaged from said oscillatory driving clutch member, an operating member common to said locking means and driven clutch member, and means whereby the movement is successively transmitted from said operating member to said locking means and then to said driven clutch member, the last mentioned means comprising a member movable longitudinally to transmit movement to said locking means and adapted to be rotated to move said driven clutch member.

In testimony that I claim the foregoing I hereunto affix my signature.

WILLIAM H. MEYER.
